SKATE SCABBARD

James B. Swett, Barrington, R.I., assignor to Brunswick
Sports Products Company, Torrington, Conn., a corporation of Delaware

Filed Feb. 24, 1960, Ser. No. 59,496

Term of patent 14 years

(Cl. D34—5)

Fig. 1 is a perspective view of a skate scabbard showing my new design, the opposite side, not shown, being substantially the same as that shown;

Fig. 2 is a front elevational view thereof; and

Fig. 3 is a cross sectional elevational view taken along the line 3—3 of Fig. 1.

The dominant features of my design reside in the portions shown in full lines.

I claim:

The ornamental design for a skate scabbard, as shown and described.
